Attorney

UNITED STATES PATENT OFFICE.

CHARLES A. HARMS, OF INDIANAPOLIS, INDIANA.

COLLAR BUTTON.

Application filed November 20, 1923. Serial No. 675,897.

To all whom it may concern:

Be it known that I, CHARLES A. HARMS, a citizen of the United States, residing at Indianapolis, in the county of Marion and 5 State of Indiana, have invented certain new and useful Improvements in Collar Buttons, of which the following is a specification.

My said invention relates to collar buttons and it is an object of the same to produce a 10 button which may be used in the manner of an ordinary collar button but which may also be used for example on a shirt the collar of which has shrunk so as to make the same too small for use in the ordinary manner.

Referring to the accompanying drawings, which are made a part hereof and on which similar reference characters indicate similar parts,

20 Figure 1 is a perspective showing my device as it appears in use,

Figure 2, a perspective of the button itself, and

Figures 3, 4 and 5 plan views partially in 25 section showing the device in use.

In the drawings reference character 10 indicates the base of the collar button which may be round substantially as in those now in use. A neck 11 extends upward from this base, said neck having a head 12. Flanges 13 extend in opposite directions from the base and they are provided at their ends with hooks 14. Figure 3 shows the device in use as an ordinary collar button 30 with the neck 11 projecting through openings 15 and 16 at the opposed edges of a shirt or other garment. In Figure 4 the button is shown in use on a shirt which is somewhat too small by reason of the shrinking 35 of the collar band or for any other reason. In this figure the neck 11 projects through the button hole 15 but the button hole 16 is engaged by one of the hooks 14 thereby affording an increase in the operative diameter of the shirt band. In Figure 5

a still further increase is afforded, the neck 11 projecting between the margins of the shirt bosom and the respective hooks 14 engaging button holes 15 and 16.

Various modifications may be made in my 50 device without departing from the spirit of the invention and therefore I do not limit myself to what is shown in the drawings and described in the specification, but only as indicated in the appended claims.

Having thus fully described my said invention, what I claim as new and desire to secure by Letters Patent, is:

1. A collar button comprising a base having a flat side, a head, and a neck, and extensions at opposite edges of the base having their ends inturned toward said neck on the same side of the base, substantially as set forth.

2. A device for securing a collar to the 65 neckband of a shirt, comprising a member having a substantially flat side, neckband engaging elements on the opposite side at the ends of said member and a collar engaging element between said neckband engaging elements on the same side of said member, substantially as set forth.

3. A device for securing a collar to the neckband of a shirt, comprising a collar engaging element having a base with a substantially flat under side, a collar-engaging neck, diametrically opposed elements on said base having their ends inturned toward each other in substantially the plane of said base to provide neckband engaging portions, 75 substantially as set forth.

In witness whereof, I have hereunto set my hand and seal at Indianapolis, Indiana, this 14th day of November, A. D. nineteen hundred and twenty-three.

CHARLES A. HARMS. [L. s.]
